UNITED STATES PATENT OFFICE.

JOSEPH W. JONES, OF NEW YORK, N. Y.

DESIGN FOR A FRAME FOR GRAPHOPHONES.

SPECIFICATION forming part of Design No. 31,921, dated December 5, 1899.

Application filed October 31, 1899. Serial No. 735,426. Term of patent 7 years.

To all whom it may concern:

Be it known that I, JOSEPH W. JONES, a citizen of the United States of America, and a resident of New York, in the county and State of 5 New York, have invented a certain new and original Design for a Frame for Graphophones, of which the following is a specification.

In reference to the accompanying drawings, 10 Figure 1 represents a perspective view of a metallic frame for a graphophone; and Fig. 2 shows also a perspective view of the same, but in an inverted position.

As shown in the drawings, the leading or 15 material feature of my design consists of a rectangular bed-plate A, having a series of depending supports or posts B, B', B², and B³, and secured to or forming part of said sup-

ports or posts and arranged some distance below the rectangular bed-plate A is a plate 20 C, which latter, together with the above-mentioned rectangular bed-plate, forms the bearings or supports for the mechanism of a graphophone.

Having described my invention, what I 25 claim as new, and desire to secure by Letters Patent, is—

The design for a frame for graphophones, as herein shown and described.

Signed by me at Philadelphia, Pennsylvania, this 30th day of September, 1899.

JOSEPH W. JONES.
